(57) **CLAIM**

The ornamental design for an operation-guiding cylinder for intraocular lens implantation device, as shown and described.

DESCRIPTION

FIG. 1 is a front view of an operation-guiding cylinder for intraocular lens implantation device showing our new design; FIG. 2 is a rear view thereof; FIG. 3 is a left side view thereof; FIG. 4 is a right side view thereof; FIG. 5 is a top plan view thereof; FIG. 6 is a bottom view thereof; FIG. 7 is a top front perspective view thereof; FIG. 8 is a bottom front perspective view thereof; and, FIG. 9 is a second front view shown in an environment. The shading on the entire surface of the article in each drawing indicates shading for depicting a three-dimensional surface shape of the article. The broken lines in the drawings are directed to environment and form no part of the claimed design.
